UNITED STATES PATENT OFFICE.

CHARLES H. BURNS, OF NEW YORK, N. Y., ASSIGNEE TO JOHN W. SURBRUG, OF NEW YORK, N. Y.

VENDING-MACHINE.

1,284,045.

Specification of Letters Patent.

Patented Nov. 5, 1918.

Application filed October 21, 1916, Serial No. 126,834. Renewed September 18, 1918. Serial No. 254,681.

To all whom it may concern:

Be it known that I, CHARLES H. BURNS, a citizen of the United States, and a resident of the city of New York, county of Bronx, and State of New York, have invented certain new and useful Improvements in Vending-Machines, of which the following is a specification.

My invention relates to machines for vending boxes of candy or any other like articles and its object is to provide a device of this character, simple in construction and positive in action.

Another object of this invention is to provide a device of this character which will be regulatable to the varying sizes of coins so that variously priced articles can be sold at various times in my improved machine without any material change or alteration being made in the door operating mechanism of the device.

With these objects in view, I have devised the construction shown in the drawings forming part hereof and specifically pointed out in the claims appended hereto.

In the drawings, hereto annexed,

Figure 1 is a vertical sectional elevation of my improved machine looking at the side wherein the operating mechanism is contained, portions of said mechanism being shown in section to clearly disclose the same;

Fig. 2 is a sectional view on the line 2—2 of Fig. 1; looking in the direction of the arrows; and

Fig. 3 is a side view of the machine, one of the sides of the casing being removed to show the method of operation of the door opening mechanism.

Throughout the various views of the drawings, similar reference characters designate similar parts.

In the preferred embodiment of my invention, as shown in the accompanying drawings, 1 indicates the box or casing which has a space 2 for containing the merchandise or article vended. The casing is provided with the usual rear wall 3, sides 4 and a hinged or swinging door 5. Adjacent one of the sides 4 is secured a vertical plate or wall 6, and the space between this wall 6 and the adjacent side wall 4 is occupied by the door operating mechanism.

A coin chute 7 is secured to the wall 6, preferably by means of pins extending through the ears 8. The door 5 is provided

with a coin opening 9, through which a coin can be passed to reach the coin chute through which it descends in the usual manner.

Beneath the lower end of the coin chute is situated a latch 10 which is pivoted on the wall 6 by means of the pin 11. In order that a coin passing through the chute 7 may pass said latch without disturbing its position, a recess 12 is formed therein. One end of the latch is provided with a hook 13 adapted to engage a hook bolt 14 secured to the door 5, and an opening 15 is provided in the casing through which said hook bolt 14 may extend to reach the latch.

In order to normally hold the hooked end of the latch into engagement with the hook bolt 14, a spring 15 has one of its ends secured to the latch and its other end extends to a pin 16. To limit the upward movement of the hooked end of said latch, a stop 17 extends from the wall 6, and the upper edge of the latch contacts with this stop thereby restricting the upward pull of the spring 15.

Below the latch 10 is a plunger 18, slidably mounted in a guide 19, and this plunger is provided with a head 20 and a threaded rod 21 upon which is adjustably mounted an abutment 22 consisting of a plate having a curved edge 23 to fit the edge of a coin, and a projecting lug 24 through which the rod 21 is threaded. The abutment 22 may be moved back and forth on this rod as desired to accommodate the varying diameters of coins used and it can be locked in any desired position on said rod by means of a suitable lock nut 25 or any other desired locking means. A spring 26 surrounds the rod 21 within the guide 19 and extends from the end of said guide to the end of the head 20 of the plunger and forces the plunger outwardly after it has been inwardly pressed by the purchaser.

Below the plunger is a coin support or rest 27, which is secured to the wall 6 by the pins 28 or in any other desired way. This coin support is adapted to catch a coin passing through the coin chute 7 and through the recess 12 in the latch and it also acts as a guide for the abutment 22, which slides therein and forces the coin held by the support against the latch to free the same from engagement with the door in a manner to be set forth.

In Fig. 3 I have shown the manner in which the latch 10 is freed from engagement

with the hook bolt 14 on the door to allow said door to open. A coin is dropped through the coin opening 9 into the coin chute 7 and it falls downwardly through the recess 12 without disturbing the position of the latch 10. The coin descends until it reaches the support 27, upon which it rests. The plunger 18 is then pressed inwardly, whereupon the curved edge 23 of the abutment 22 bears against the edge of the coin, indicated at 31, (Fig. 3) and moves said coin along the support 27 until the edge of the coin forcibly contacts with the end 29 of the recess 12 so that the latch 10 is pivoted about its axis 11 until it assumes the position shown in Fig. 3, with its hooked end 13 free from engagement with the lock bolt 14 whereby the door 5 is swung open by a spring as indicated at 30 or any other desired form of spring. The inward movement of the plunger continues until the abutment reaches the position shown in dotted lines in Fig. 3 and the coin is pushed off the support, and falls downwardly to the bottom 25 of the casing as indicated at 32.

The spring 26 forces the plunger back to the position shown in Fig. 1 and the spring 15 brings the latch back to the position shown in that figure and the door is 30 shut in the usual manner.

Having described my invention, it is obvious that the same is not to be restricted to the exact embodiment herein shown but is broad enough to cover all structures coming 35 within the scope of the annexed claims.

What I claim is:—

1. A device of the class described having a casing, a movable door for the same, a latch engaging the door, a coin support, a 40 plunger and an adjustable abutment on said plunger for moving the coin on its support against the latch to free said latch from engagement with the door.

2. A device of the class described having 45 a casing, a movable door for the same, a

pivoted latch engaging said door, a coin chute above said latch, a coin support below said latch, a plunger, an adjustable abutment on said plunger for bearing against said coin while said coin is resting on its support and forcing said coin against the latch whereby said latch is disengaged from the door.

3. A device of the class described having a casing, a pivoted door therefor, a pivoted latch having one of its ends detachably engaging said door, a coin chute, a coin support below said chute and latch, a plunger interposed between the plunger and coin support, an adjustable abutment on said plunger for engaging a coin resting on the support and forcing the same against the latch, adjacent the free end of said latch, whereby said latch is disengaged from the door.

4. A device of the class described having a casing, a pivoted, spring actuated door, a pivoted latch for engaging said door and holding the same normally closed, said latch being recessed to allow a coin to pass the same, a coin support below the latch, a plunger and an adjustable abutment on said plunger for forcing a coin against the latch and moving the same out of engagement with the door.

5. A device of the class described having a casing, a pivoted door therefor, a projection on said door, a pivoted latch having one of its ends engaging said projection and a spring for holding said latch normally in engagement with the door, a coin chute above the latch, a coin support below the latch, said latch being recessed to allow a coin to pass the latch and reach said support, a plunger between the support and the latch, 85 an adjustable abutment on said plunger for engaging a coin while on the coin support to force said coin against the latch and free the same from engagement with said projection.

CHARLES H. BERNS.
